CLAIM

The ornamental design for an animal treat dispensing container, as shown and described herein.

DESCRIPTION

FIG. 1 is a side, front perspective view of an animal treat dispensing container;

FIG. 2 is an opposite side, front perspective view of the animal treat dispensing container in which a cap component is shown removed from a dispensing opening;

FIG. 3 is a front perspective view of the animal treat dispensing container in which a portion of the cap component is positioned on a rear side of the container; and,

FIG. 4 is a rear perspective view of the animal treat dispensing container in which the cap component is secured to a rear retainer.

1 Claim, 4 Drawing Sheets
